TUBE ALIGNING MECHANISM

Frank J. Cozzoli, Plainfield, N. J.

Original application February 12, 1943, Serial No. 475,625. Divided and this application December 20, 1943, Serial No. 514,929

11 Claims.

(CL. 198—20)

The present invention relates to improvements in article feeding means and more particularly to an improved mechanism for feeding attenuated and relatively small bored containers to and upon the shanks of tubular needles in preparation for subsequent processing.

The present application is a division of my prior application Serial No. 475,625, filed Feb. 12, 1943, and the invention hereof has for a primary object, to render available a mechanism adapted automatically to bring the relatively small bore of a glass tube, an ampule for example, and the free end of the needle to be received therein, into concentric relation prior to telescoping of the needle and tube, to the end that such telescoping may be effected without danger of fracturing or splintering the glass of the ampule. Because of the fragileness of the necks of the ampules and the tendency of the needles on which they are to be mounted, for washing, filling etc. to become out of alignment, the loading has heretofore been effected manually by one or more attendants and, in consequence, the rate of movement of the tubes through their successive processing operations was slowed to the rate of hand loading. The automatic centering and loading features of the present invention relieves the operator of the machine of the strain and effort involved in the mutual centering of the needles and tubes and the subsequent processing of the containers is, accordingly greatly accelerated.

The invention is particularly useful in feeding ampules or other small apertured bottles or tubes on to needles of a washing machine. In the washing of such containers, tubular needles are used to deliver the washing fluid, to the interiors of the containers, and the needles themselves must be introduced into the containers and project thereinto a distance sufficient to convey the liquid past the restricted necks thereof so that a relatively free passageway along the exterior of the needle remains for the escape of air displaced from within the body of the container. The liquid being injected into the body of the container by way of the restricted or attenuated neck is confined within the bore of the needle and does not prevent the outflow of air. Small bored bottles, vials, ampules, etc. are thus washed or filled with liquid preparation quite expeditiously after the needle is inserted into the container.

The small size of the container necks demands, of course, still smaller diametered tubular needles and although they are initially straight some

5 become, after a period of usage, somewhat curved. The present invention affords an automatic means for centering the ends of needles that may be out of alignment with the container end about to be placed thereon. In a similar way, the invention undertakes to provide a means for centering the needle receiving opening of the container with the needle about to be introduced thereto, so that containers that may be slightly deformed or have their necks slightly offset from 10 true, may be used and fed along with the perfectly formed container. While the container maker's aim is perfect uniformity, that end is very difficult to achieve especially in the glass blowing and drawing art. The present invention automatically aligns the needle with the small opening in the container and so provides for such minor irregularities that may exist between individual containers and needles.

15 A further aim of the invention is to render available a tube feeding mechanism capable of accommodating containers of different body diameters and different lengths simultaneously or in successive runs, so that containers of a wide variety of sizes may be automatically centered and mounted upon tubular needles correspondingly different in size.

20 For purposes of illustration, the present invention is disclosed in conjunction with an ampule washing machine having a conveyor structure with a series of transversely extending trough assemblies, each of which carries one or more radiating tubular needles on which the tubes to be cleaned are located. In the instant embodiment the trough assemblies are removably attached to the links of chains that pass over cog wheels intermittently revolvable on horizontal axes. As the cogs are intermittently actuated, the troughs and needles pass from the under 25 side of the wheel axis to a horizontal position where synchronously driven tube feeding mechanisms aligns the tubes and needles and places the tubes on the needles. The next movement of the conveyor lifts the tubes out of the loading mechanism, and subsequent movements places them in a vertical position, with their open ends down. Each trough assembly is formed with a laterally extending common conduit in communication with each of the needle 30 jets, and whose outer end is adapted to be engaged successively by each of a series of independent fluid supply nozzles. The supply nozzles are normally stationary relative to the movement of the troughs, but have a reciprocating motion timed with the conveyor movements so

that after each trough arrives at a station a connection is made with a separate fluid system and the particular cleaning fluid or agent of that system is forced through the supporting needles to the interior of the inverted tubes. In the present embodiment eight effective stations have been illustrated, and as one may desire to follow each injection of cleaning fluid with a drying medium, four of the stations might be termed cleaning stations and the intervening four, drying stations. The invention, however, comprehends other uses for the loading mechanism and the foregoing example is but representative of a typical use of this invention.

During the period of rest of the conveyor additional tubes are being fed and located on the needles at the loading station, by means driven by the conveyor driving means, and the thoroughly cleaned tubes are being discharged from the needles at the end station on to a conveyor or other mechanism leading to packaging or filling devices. The operation is such that the attendant merely places unclean tubes, which may be of like size or of different sizes, in the loading channels, after which they are automatically aligned with the washing needles, placed thereon, and moved through the successive cleansing, sterilizing and drying stations, and the sterile tubes thereafter discharged upon a conveyor or receiving means ready for the subsequent operations of filling and sealing. The washing operation is continuously intermittent and allows just enough dwell period at each station to insure proper loading, proper connecting and disconnecting of the fluid lines, and cyclic operation of the control valves, to insure adequate sterilization and drying time without waste or mixing of the ingredients. Following the initial operation of placing unclean tubes in the feeding racks, the machine operation is entirely automatic in its functioning.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like character of reference denote corresponding parts throughout all the views, of which:

Figure 1 is a side view of a washing machine constructed in accordance with this invention.

Fig. 1A is a fragmentary view of a portion of the machine illustrated in Fig. 1 equipped with a preferred form of loading mechanism.

Fig. 1B is a plan view of the loading mechanism illustrated in Fig. 1A.

Fig. 1C is a vertical sectional view taken substantially along line 1c—1c of Fig. 1B.

Fig. 2 is an end view thereof, partly in section better to illustrate the drive means and the mechanisms for coordinating the movements of the several elements and controls.

Fig. 3 is a plan view of a loading mechanism.

Fig. 4 is an end view thereof; Fig. 5 is an enlarged view of a portion of the tube and needle aligning means; and Fig. 6 is a sectional view taken through one of the loading troughs and aligning means.

Fig. 7 is a vertical sectional view taken substantially along line 7—7 of Fig. 3.

Referring more particularly to Figures 1 and 2, the washing machine illustrated is mounted upon a pair of leg standards 10, and comprises essentially, a pair of lower rails 11, 12 and a pair of upper rails 13, 14, between which a series of bearing plates 15, 16, 17, 18 are secured. The construction is such that by using increased or decreased lengths of rails 11—14, and adding or removing pairs of bearing plate units 15—18, the length of the machine may be altered and its capacity changed to suit specific requirements without expensive reconstruction or time consuming delays. This improved structure is more fully set forth and claimed in my copending application Ser. No. 514,930.

The supporting rails 11—14 are spaced apart, as in Fig. 2, and the channel therebetween contains substantially all of the actuating mechanisms. The conveyor mechanism also travels between the supporting rails and includes two linked chain structures 19 and 20, whose pivot rolls 21 engage notches 22 in driving and driven pairs of star wheels 23 and 24. The wheels 23 and 24 are fixedly mounted to shafts 25 and 26, respectively, and these are journaled in bearing blocks 27 and 28 supported by the main frame. Between the pair of star wheels 23 a ratchet wheel 29 is fixed and adapted to be driven intermittently by means of a spring pressed pawl 30 mounted at the end of an actuating lever 31. The other end of the lever is pivoted to a cross support at 32 in such a position that a central portion of the lever overlays an actuating cam or roller 33 mounted upon a main cam shaft 34.

A motor 35 drives the main shaft through reduction gearing in a housing 36, and when operating the actuating arm 31 is caused to be raised and lowered once during each complete turn of the cam shaft. Each time the arm is lifted the pawl 30 engages a notch in the ratchet wheel and indexes the wheel one position. Such movements, it will be seen, advances the conveyor step by step in a counterclockwise direction (in Fig. 1), leaving a dwell period between steps for loading and cleansing operations.

The links of the two conveyor chains are disposed directly opposite one another and are bridged by removable needle trough assemblies 40 each of which comprises an open ended trough member 41 having a plurality of aligned tube supporting hollow needles 42 radiating therefrom. Each needle is screw threaded to the bottom of a trough and its interior arranged to communicate with a common conduit 43 formed in the trough bottom. The conduit is closed at one end and its other end is provided with a valve seat 44 which is adapted to cooperate intermittently with the valved end of fluid supply conduits 45.

In the present embodiment, eight supply stations and eight supply nozzles 45 have been illustrated. The number may, however, be increased or decreased as desired. Each of the nozzles 45 is normally spring pressed toward the valve seat 44 in a related trough assembly by a spring 46 operating between a loose collar 47 and a normally tight collar 48. By adjusting the tight collar to the left (in Fig. 2) the particular nozzle effected may be prevented from moving.

The several nozzles are actuated outwardly by means of levers 49 that are secured to an oscillatable shaft 50 journaled in brackets 51 secured to the framing. Another lever 52 is also secured to the shaft 50 and has its lower end pivotally connected to one arm of a bell crank lever 53 which in turn is pivoted at 54 in a bracket se-

cured to the framing. The other end of the bell crank 53 carries a roller 55 that tracks on the periphery of a cam 56 secured to the cam shaft 34. Part of the surface of the cam 56 is relieved to provide a low portion into which the roller 55 drops during the movement of the conveyor. When the conveyor and the trough assemblies 40 have been indexed, the high portion of the cam 56 engages the roller 55 and actuates the bell crank clockwise from the position illustrated in Fig. 2. This movement through the toggle-like connection with lever 52 rocks the shaft 50 and levers 49 in a counterclockwise direction and the supply nozzles move inwardly and seat upon the respective valve seats in the trough assemblies.

After the nozzles are seated, a valve 60 associated with each supply line, is opened and fluid is directed through one or more of the lines 61, nozzles 45, and conduits 43 of the trough assemblies 40. Normally the valves 60 are closed, and are opened only when their respective valve stems 62 are depressed.

The means for opening the valves comprises a series of adjustable screws 63 carried at the free end of a pivoted bracket 64, each of which may be set so as to effect opening of its related valve to a greater or lesser extent depending upon requirements. The inner end of the bracket is pivoted to the framing, and carries an actuating arm member 65. The arm 65 mounts near its lower end, a roller 66 that engages a cam 67 mounted on the cam shaft. The cam 67 progresses from minimum to maximum diameter (see Fig. 2) so that the valves are gradually opened and quickly closed. The angular setting of the cam 67 on the cam shaft 34 is co-operatively related with the movements of the conveyor so that the opening and closing of the respective valves is timed to occur during the period of dwell of the trough assemblies at the different stations, and between the interval of seating and unseating of the supply nozzles, to the end that no cleaning fluid flows to the needles until all connections are tight. The setting of the individual set screws 63 controls the volume of fluid supplied to the different groups of needles at the different stations.

The valve actuating arm 65 is guided near its lower end in a lug 68 at the side of the machine and the extreme lower end 69 projects therethrough to engage, during a certain portion of its travel, the plunger 70 of a sensitive switch 71. The switch 71 is normally open and is connected to the drive motor in parallel with a manually operated normally open switch 72. When the operator actuates the switch 72 to a closed position, the motor 35 operates to drive the cam shaft 34 and the parts connected therewith of which the valve actuating and switch control arm 65 is one. The cam shaft will make approximately one-quarter of a turn before the end 69 engages the plunger 70 and closes the switch 71. When this occurs the operator may release switch 72. Power operation continues until the cam roller 66 rides off the high part of the cam 67. At this point the valve actuating screws 63 are quickly lifted, allowing the valves to close, and the stem 69 lifts away from the switch plunger 70 and the switch 71 opens. The drive motor thereupon stops and the machine comes to rest with all valves closed; and with the loading mechanism retracted to a position ready to receive tubes. Spring elements 73, 74 and 75 assist in the retracting movements of the several elements.

With this simplified form of control, the ma-

chine may be operated continuously, by maintaining the foot switch 72 closed, or cyclically by the intermittent actuation of the foot switch. With either method of operation, however, the operation of the holding switch 71 is such as to insure that the fluid valves 60 are actuated to closed position by the time the main drive ceases operation. If desired the switch 71 may be located and arranged to be operated directly by a separate cam similar to the cam 67, or from other moving parts e. g., the loading slide 80.

Cooperatively related with the indexing of the troughs is the operation of the loading mechanism illustrated more particularly in Figs. 1A, 1B and 1C, and a variant form in Figs. 1-6. The function of the loading mechanism is to position the unclean ampoules or tubes on the several needles of successive trough assemblies during the time they are at rest. Advantageously, a horizontal position of the needles, as illustrated in these figures, is selected as the loading station. The loading mechanism comprises a reciprocable carrier 80 that is guided on the rails 13 and 14 and actuated toward and away from the needles by mechanism driven from the common cam shaft 34. A cam element 81 having a gently rising side and a relatively steep side, is mounted upon the cam shaft 34 for that purpose and engages a roller 82 carried by a pivoted lever 83. The lower end of lever 83 connects with generally horizontal link member 84 which in turn connects with the lower end of a pivoted lever 85. The upper end of the lever 85 has a pin and slot engagement 85a with the under side of the carrier 80, and as the main cam shaft rotates, the loading mechanism is reciprocated in timed relation with the conveyor movements. A heavy spring 86 normally tends to urge the roller 82 against the cam 81 and the feed carrier 80 to retracted position.

As illustrated in the drawings, each trough assembly carries six needles whereby six ampoules or tubes may be loaded and subsequently washed simultaneously. Likewise in the tube carrier 80 there are six channels 86 into which unclean tubes are to be laid. The forward portions of the channels 86 are somewhat tapered as at 87 and serve to guide the forward ends of the tubes into coaxial alignment with the needles. In the preferred form of loading mechanism shown in Figs. 1A and 1B and 1C the feeding and aligning of tube and needle is effected pneumatically during the forward travel of the carrier 80, whereas, in the form illustrated in Figs. 1-6, the feeding and aligning is effected mechanically by the overtaking action of the individual plungers 88 which urge the respective tubes into the polished cone shaped recesses 89 provided in centering fingers 90. The centering fingers 90 move forward with the carrier 80 and are provided with similar cone cavities 91 in their sides facing the needles. Thus as the carrier advances, the several needles, should any be not perfectly straight, are guided by the cone walls 91 through a central opening 91a therein and into the ampoule or tube that is centered in the cone on the other side.

With reference to the feeder illustrated in Figs. 3 and 4 each plunger 88 carries at its forward end a yielding abutment or pusher 92 that is compressed slightly when the rim of the tube or ampoule has been advanced into the cone 89 as far as it will go.

When, however, the machine is equipped with pneumatic feeding means, a jet of air directed at the rear end of each ampoule, urges the respec-

tive ampules forward along the channels and into the cones 89, without subjecting the ampules to physical contact with the ends of the feed plungers. Referring, particularly to Figs. 1A, 1B and 1C, the slide 80 carries a series of air jets 88^a one located in each of the channels 86, which receive compressed air from a common manifold 88^b. The forward end of each air jet tube 88^a is provided with a small opening 88^c through which a stream of air is forced at the proper time and which move the tubes lying in the channels 86 therealong and into the cones 89. The air for the jets is controlled by a normally closed valve 88^d secured to the frame, and which is opened automatically during the forward movement of the slide and closed again during the return movement.

To effect this operation, a pivoted valve actuating lever 88^e is provided, the under side of which is formed with a cam surface 88^f adapted to track upon a roller 88^g of the slide. As the slide moves forward, the roller 88^g rocks the lever about its pivot and depresses the valve stem, thus admitting the air to the manifold 88^b and the jets 88^a. When the pressure is on, the ampules immediately move forward into the cone chucks and are held by the streams of air pressure in positions ready to receive the needles. When the chucks open, the air streams continue to push the ampules forward well on the needles. Ahead of the control valve 88^d a cut-off valve 88^h may be installed for closing off or regulating the volume, and ahead of the valve 88^d a pressure reducing or regulating valve (not shown) may be installed. The latter is desirable in installation where the line pressure is too high. A jet pressure of approximately 5 pounds will advance medium size ampules efficiently. Larger and smaller tubes or heavier and lighter tubes will naturally require increased or decreased jet pressures. The air from the control valve is directed to the jets 88^a through a line 88ⁱ and a flexible hose 88^k, the latter type of connection provides for the movement of the carriage 80 and jets 88^a relative to the fixed control valve.

The centering cone elements 89 and 91 are formed in two parts, each part being pivoted to the carrier at 93, some distance below the conical seats, and one leg 94 of each pair is pivoted to an actuating rod 95 and the other leg 96 of each pair, is pivoted to another actuating rod 97. A spring 98^a connects with opposite ends of both rods and is tensioned normally to hold all of the cones in closed position (full line position in Fig. 5). As the carrier 80 travels forward, in response to the action of the cam 81, rollers 95^a and 97^a carried at the ends of the rods 95 and 97, engage stationary cams 98 and 99, and at the end of the forward movement, the incline of the stationary cams react to force the rods inwardly thereby effecting opening of the cones, i.e., to the position illustrated in dotted lines in Fig. 5. By the time this occurs the cleaning needles will have been centered and caused to project well into the ampule or tube necks and the succeeding indexing movement of the conveyor will effect a lifting of the ampules out of the channels 86 through the then opened centering cones. Just prior thereto, however, the opening of the centering cones permits the compressed air or the spring cushions 92 to push each tube forward further on the associated needle so that the ampules are well forward on the needles at the time indexing occurs, and consequently cannot fall off.

The means for advancing the plungers 88 rela-

tive to the carrier in the form illustrated in Figs. 1 and 4 comprises a sliding frame 100 that is guided on rods 101 that form part of the traveling carrier 80. The carrier also mounts at its rear portion, a pair of supporting rollers 102 rotatably mounted on a shaft 103. Each roller bears upon a track plate 104 secured to the main framing. The shaft 103 pivotally mounts a short lever 105 which has a pin and slot connection 105^a with the underside of the sliding frame 100, and by means of a rod-like extension 106, extends through an aperture 107 in a stationary cross-plate member 108. Accordingly, as the carrier 80 moves forward, from the position illustrated in Fig. 1, the rod 106 fulcrums on the sides of the opening in the crossplate and rocks the lever 105, and the movement of the lever 105 is transmitted to the slide 100 and plungers 88 secured thereto, whereby the latter move forward slightly faster than the forward movement of the carrier. A helical spring 109, having one end connected with the free end of the lever 106 and its other end connected with a support 110 depending from the carriage 80, cooperates to advance the plungers 88 relative to the carriage as the latter is propelled forward, and renders the plungers as a group slightly yieldable. This mechanism is not necessary when the pneumatic feeder is employed.

The action of the various elements, on reverse movement of the carrier (to allow a succeeding needle group to move into loading position), is just the reverse to that explained, with the result that ample space between the air jets or plungers and the centering cones is provided to permit easy insertion of unclean tubes into the channels.

In order that the loading mechanism be adapted for tubes of different length, each plunger 88 is adjustable endwise relative to the slide 100. Set screws 100^a are provided to lock each plunger in adjusted position. The dotted lines in Fig. 3 illustrate the lower three plungers adjusted outwardly to accommodate slightly longer tubes. All plungers are, however, similarly adjustable and in consequence two or more sizes of tubes may be loaded and sterilized simultaneously. When necessary, one or more of the needles in the trough assemblies, may also be replaced by needles of a size best adapted to support the particular tubes to be sterilized. For exceptionally large tubes, the stationary cams 98 and 99 and the fulcrum plate 108 may be shifted rearwardly the requisite amount to allow correspondingly long needles to swing into position in front of the centering cones. With the machine equipped with the pneumatic feeder, all of the jets may be adjusted as a unit toward or away from the cone chucks, and if different length tubes are to be run simultaneously jet tubes of different lengths may be mounted in the slide and manifold.

As the needle assemblies move upwardly about the star wheel center 26, carrying and supporting thereon the ampules or tubes, the tubes should any be not fully down on the needles, are caused 65 to settle thereon and are then carried along the top of the conveyor in an inverted position through the eight sterilizing stations. At the station *a*, hot water, for example, may be injected into the interior of the tubes through the needles and connections heretofore explained, and at the next station *a'*, air or other drying medium. At the third station *b*, another cleansing fluid, not necessarily water, may be injected followed by a drying or expelling medium at station *b'*, and 70 similar cleansing and sterilizing operations per-

formed at stations *c*, *c'*, *d*, and *d'*, thus insuring a high degree of sterility.

Although it is not essential, it has been found convenient to group the cleansing stations in pairs, as above mentioned, for the reason that the valves controlling the several fluid supply lines are opened after the trough assembly arrives in position, and closed before the assembly leaves that position and all the while liquid is draining from the inverted tubes into the troughs. This draining may continue during the transit from the first station of a pair to the second and in the interests of conserving and reclaiming, without mixing the different fluids, the fluid that drains from the ampules and trough while at the second station (of any pair) should be collected with the fluid that drains from the trough at the first station of the pair. This objective may be achieved by providing a plurality of catch basins 110 along the path of travel under the lips of the troughs. In the instant example four of such basins have been provided and each has an opening 111 therein which may be plugged, as illustrated, in Fig. 2, or piped to appropriate reclaiming apparatus or to reservoirs. Such liquid that may drip from the sides of the troughs during their travel about the conveyor is collected in an underlying pan 112 from which it escapes to a sump through a pipe 113.

As illustrated in Figs. 1 and 2, the ampules or tubes are prevented from being blown off the needles when the pressure is applied, by a vertically adjustable cover 114. This cover is open ended and normally is set to clear the bottoms of the inverted tubes without allowing the tubes too much end play therebetween.

At the completion of the several cleaning cycles the sterile tubes are carried from under the cover 114 and removed or discharged from the needles. In the embodiment illustrated herein an adjustable guide plate or chute 115 is provided on which the tubes are laid as the needles reach a position below the horizontal. When this occurs the sterile tubes automatically slide off the needles onto the chute and thence on to a conveyor belt 116. The link connection 117 and pin and recesses 118 afford means for adjusting the chute to different tube sizes.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:

1. A washing machine combining an indexible container carrier, a series of receiving spindles carried thereby, each of said spindles being adapted to mount a container to be washed, feeding means cyclically operable to locate and feed containers on to said receiving spindles comprising pairs of conically recessed jaw members and associated feed plungers spaced therefrom, means for advancing said plungers toward said jaw members thereby to urge the containers positioned ahead of the plungers into the cone shaped recess in said jaws, means for indexing said re-

ceiving spindles successively into alignment with the axis of said cone shaped jaws and for holding same in said position, means thereafter operable to advance said plungers and said jaw members relative to said receiving spindles thereby to position the containers in mounted position on said spindles, and means for actuating said jaw members to open position prior to an index movement of the carrier.

10 2. The combination set forth in claim 1 including means operable subsequent to the positioning of the containers on the spindles and following the opening of said jaw members to advance the containers further on said spindles prior to an indexing movement of said carrier.

15 3. A washing machine having a series of indexible container receiving supports, each of said supports being adapted to mount a tube to be washed, in combination with feeding means cyclically operable to locate and feed containers to said receiving supports comprising pairs of conically recessed jaw members and associated axially movable feed plungers spaced therefrom, means for advancing said plungers toward said jaw members thereby to urge the leading ends of containers placed therebetween into concentric relation with said cone shaped jaws, means for axially aligning said supports with the axis of said cone shaped jaws and for holding same in said position, means thereafter operable to advance said plungers and said jaw members relative to said receiving supports thereby to position the containers carried therebetween in mounted position on said receiving supports, and means for opening said jaw members in timed relation with the indexing movements of said supports.

4. Ampule and supporting spindle aligning and mounting means comprising a group of laterally spaced and generally parallel spindles adapted to mount ampules and movable intermittently from a loading station to a processing station, a relatively reciprocable carriage member at the loading station provided with ampule receiving channels laterally spaced therein in accordance with the spacing of said spindles, means for feeding ampules to be processed along said channels toward said spindles, oppositely facing ampule and spindle centering means at the end of each of the channels, and means for advancing said carriage and centering means toward said spindles when the latter are in a position of rest at the loading station, said ampule and spindle centering means being operative to align the open end of each ampule with an associated spindle and to guide the spindle centrally into the interior of the ampule during the loading operation.

5. A machine having a series of slender spindles adapted to support relatively small bore tubular containers and means for indexing said slender spindles from station to station, combining means for loading glass tubes on said slender spindles comprising a reciprocable carriage member having one or more tube receiving channels therein generally aligned with associated slender spindles, centering fingers at the end of each of the channels adjacent said spindles, said fingers having tube centering means disposed at one side and having axially aligned spindle centering means disposed on the other side, means timed with the indexing movements of said spindles for advancing tubes along said channels toward said centering fingers and said carriage and tubes bodily toward said spindles thereby automatically to bring the tubes and spindles into

axial alignment just prior to the time the tubes telescope the spindles, and means for actuating said centering fingers and said carriage between index movements of said spindles to permit the carrier and spindles to index.

6. In a machine having a series of slender spindles adapted to support relatively small bore tubular containers, the combination of means for loading containers on said spindles comprising a reciprocable carriage member having one or more tube receiving channels formed therein, pairs of centering fingers at the ends of the channel adjacent said spindles, said pairs of fingers having tube centering means disposed at one side and having axially aligned spindle centering means disposed on the other side and apertures therethrough to receive the spindles, means for advancing tubes along said channels toward said centering fingers and said carriage and tubes bodily toward said spindles thereby automatically to center each tube and its associated spindle just prior to the time the spindles are telescoped by the advancing tubes, and means for opening said centering fingers after telescoping starts.

7. The combination set forth in claim 6 including means for varying the effective action of said container advancing means to suit different container lengths.

8. In an ampule washing machine having a carrier mechanism adapted to receive and transport one or more ampules to be processed, combining means for loading ampules to be processed on said carrier comprising an ampule supporting member, said member having a channel formed therein to receive the ampule to be processed, and pneumatic means approximately axially aligned with said channel and situated to the rear of the ampule placed therein for advancing the ampule along the channel, and control means actuated in timed relation with the carrier movements for controlling the action of said pneumatic means and thereby the movement of the ampule placed in the channel.

9. In an ampule washing machine having a carrier mechanism adapted to receive and transport one or more ampules to be processed, combining means for loading ampules to be processed on said carrier comprising an ampule supporting member, said member having a channel formed therein to receive the ampule to be processed, and pneumatic means for moving the ampule along the channel toward said carrier mechanism, including a control valve and actuating means therefor timed with carrier movements.

10. A means for mounting a small bored tube upon an elongated support comprising a chan-

neled carriage member adapted to carry a tube and to transport same in the direction of the longitudinal axis of the support, tube centering and support centering means movable with said channeled carriage comprising a pair of normally closed jaw members having cone shaped recesses formed in opposite sides thereof with the apexes of the recesses toward each other and terminating in an aperture slightly larger than the size of said elongated support for receiving the latter therethrough, means for advancing a tube in the channel of the carriage toward the cone-shaped recess formed in one side of the jaw members thereby to position the end of the tube in concentric relation with the aperture in said jaw members, means for advancing said carriage and jaw members toward said support thereby to effect a centering of the support with the aperture in the jaw members and to cause the centered end of the support to project through the aperture and into the tube centered by the walls of the cone recess at the other side of said jaw members, and means thereafter operable to open said jaw members to release said support and telescoped tube therefrom.

11. A means for bringing a small bored tube and an elongated support into telescoping relation comprising a member adapted to carry a tube and to transport same in the direction of the longitudinal axis of the support, tube centering and support centering means carried by and movable with said member comprising a pair of normally closed jaw members each having a cone shaped recess formed in opposite sides thereof with the apexes of the recesses extending toward each other and terminating in a coaxial aperture slightly larger than the size of said elongated support for receiving the latter therethrough, supplemental means for moving a tube relative to said member toward the cone shaped recess in one side of the jaw members thereby to center the end of the tube with the coaxial aperture in said jaw members, means for advancing said members toward said support thereby to effect a centering of the end of the support with the aperture in the jaw members and to cause the centered end of the support to project through the aperture and into the tube centered by the walls of the cone recess at the other side of said jaw members, means for opening said jaw members to release said support and telescoped tube therefrom, and means operable upon the opening of said jaw members to effect further telescoping movement between said support and the tube.

FRANK J. COZZOLI.
